METALLIC CONTAINER

George Trautvetter, Jenkintown, Pa., assignor to
Heinz Manufacturing Company, Philadelphia,
Pa., a corporation of Pennsylvania

Application April 19, 1950, Serial No. 9,328

Term of patent 14 years

(Cl. D58—17)

To all whom it may concern:

Be it known that I, George Trautvetter, a citizen of the United States, residing in Jenkintown, in the county of Montgomery and State of Pennsylvania, have invented a new, original, and ornamental Design for a Metallic Container, of which the following is a specification, reference being made to the accompanying drawings, forming a part thereof.

Fig. 1 is a front perspective view of a metallic container, showing my new design;

Fig. 2 is a bottom plan view thereof;

Fig. 3 is a top plan view thereof;

Fig. 4 is a side elevational view thereof.

I claim:
The ornamental design for a metallic container, substantially as shown.

GEORGE TRAUTVETTER.
